United States Patent

Des. 242,489
Patented Nov. 23, 1976

242,489

MOUTHPIECE FOR BREATH TESTING DEVICES OR THE LIKE

James E. Burroughs, Mount Prospect, Ill., assignor to
Borg-Warner Corporation, Chicago, Ill.

Filed Jan. 2, 1974, Ser. No. 430,287

Term of patent 14 years

Int. Cl. D24—02

U.S. Cl. D83—1 N

Published under the second Trial Voluntary Protest
Program on Feb. 10, 1976, as document No. B430,287

FIG.1

FIG.2

FIG.3

FIG.4

FIG.5

FIG. 1 is a perspective view of a mouthpiece, the broken lines representing the breath testing unit being shown for illustrative purposes only;

FIG. 2 is an enlarged perspective of the mouthpiece of FIG. 1, taken from a second viewpoint;

FIG. 3 is a top plan view of the mouthpiece of FIGS. 1 and 2;

FIG. 4 is a view in elevation of the mouthpiece of FIGS. 1 to 3; and

FIG. 5 is a bottom plan view of the mouthpiece of FIGS. 1 to 4.

I claim:

The ornamental design for a mouthpiece for breath testing devices or the like, as shown and described.
